EMERGENCY SHUTOFF FOR STEAM LINES
AND THE LIKEJoseph Kaye Wood, New York, N. Y., assignor to
General Spring Corporation, New York, N. Y.,
a corporation of New York

Application June 21, 1941, Serial No. 399,068

1-Claim. (Cl. 137—139)

This invention relates to means for controlling the flow of dangerous fluids from lines connected to reservoirs of such fluids, for example steam from steam lines connected to steam boilers operated at substantial pressures, and particularly to means for automatically shutting off the steam or the like from a line that has been damaged by shock.

In the operation of naval vessels under war conditions, one of the principal dangers to the crews of steam driven naval vessels is the danger from scalding due to breakage of steam lines. Such breakage is more frequently caused by the dynamic force or shock produced by the explosion of a mine or torpedo against the side or bottom of the ship than by a direct hit upon the steam line itself. If the steam flow to a broken steam line be not promptly shut off at the boiler, the water contents of the boiler, by reason of the reduced pressure resulting from the break, will flash into steam and flood with live steam the compartment or region in which the break occurs, with serious consequences to any crew members who happen to be anywhere near the break.

A general object of the present invention is to provide means for automatically shutting off the steam or other dangerous fluid from a line connected to a reservoir of such fluid, e. g., a steam boiler that has been subjected to a shock of such force that it causes or is likely to cause breakage of the line.

Since the steam lines of steam operated naval vessels are, in the operation of the vessels, normally subjected to dynamic forces or shock forces of considerable intensity, for which provision is made in their mounting, such forces being those arising from the firing of the guns of the vessel itself, the operation of the power plant of the vessel, the pounding of heavy seas, etc., and since the safety and effectiveness of the ship in battle may depend upon its maneuverability and instant response to its controls, it is important that any means for effecting the automatic shut off of the steam flow to a steam line shall not operate within the range of disturbances which the steam line is designed to withstand.

To insure operation only when required, the present invention contemplates the employment of an inertia member so connected to the steam main, for the protection of which it is intended, that it will partake of the ordinary movements of the main brought about by the dynamic forces to which it is ordinarily subjected but when the main is subjected to a greater than ordinary dy-

namic force, for example five times gravity (if that is the maximum accelerating force which the steam line is designed to withstand in the direction concerned) or more, the weight will then move relatively to the steam main to close an electric circuit controlling the operation of the shut-off valve.

Because of the usually substantially instantaneous action of the dynamic forces against which the device of the present invention is intended to afford protection, such as the explosion of a mine or torpedo, it is desirable that the completed electric circuit remain closed for a sufficient length of time to insure the operation of a main control switch governing the operation of the valve-operating mechanism. An important feature of the invention, therefore, is means, either mechanical or electrical, for insuring the maintenance in its closed condition of the circuit brought about by the operation of the inertia member.

Other objects and important features of the invention will appear from the following description and claim when considered in connection with the accompanying drawing, in which

Figure 1 is a vertical section on the line 1—1 of Figure 2 through apparatus embodying the present invention;

Figure 2 is a plan view, with the cover removed, of the apparatus shown in Figure 1, and

Figure 3 shows the apparatus connected to an electrically operated shut-off valve for controlling the input of steam into the main on which the apparatus is mounted.

In the illustrative embodiment of the invention, a cylindrical housing 2, having a removable cover 4 and a bottom 6 provided with threaded openings 8 to receive screws of attaching means by which the housing may be attached to the steam pipe or other device requiring emergency protection, serves as a guide for the inertia member 10. The inertia member 10, as herein shown, is a cylindrical block of metal or other suitable material of a size and weight suitable for the purposes of the present invention.

The inertia member 10 is preferably maintained at an intermediate position in its guide housing 2 by means which connect it to the housing 2 for movement with the housing under ordinary conditions. The illustrative means for suspending the inertia member 10 at an intermediate point in its guide housing 2 comprise shear pins 12 located in holes 14 drilled through the side walls of the guide housing 2 at 90° spacings about the axis thereof and entering

registering openings in the inertia member 10. These pins 12 are of such dimensions and of such material that they will serve to secure the inertia member 10 to the guide housing 2 to insure movement of the inertia member with the housing for moving forces applied to the housing up to a predetermined dynamic limit. When a dynamic force of sufficient intensity is applied to the guide housing 2 through the steam pipe or other device to be protected, to which it is connected, the inertia of the member 10 will then bring about a sufficient relative movement of the member 10 and the guide housing 2 to shear off the shear pins 12. Advantage is taken of the movement thus produced when a dynamic force above a predetermined amount is applied to the guide housing 2 to bring about the actuation of the danger preventing means such, for example, as an electrically operated shut-off valve between a steam generating boiler and the steam line upon which the apparatus of the present invention is mounted.

As herein shown, the movable member 16 of an electric switch having contact members 18 and 20 is so located beneath the inertia member 10 that when said member 10 moves toward the base 6 of the guide housing 2 it will cause the switch member 16 to bring its contact 18 into engagement with the contact 20 carried by the base 6. The movable member 16 of the switch is insulated as shown at 22 from the base 6 and is connected to one side of an electric circuit which enters the housing 2 through the insulated opening 23. The other side 28 of the electric circuit is grounded upon the guide housing 2 with which the contact 20 of the switch is also in grounded connection.

Movement of the inertia member 10 downward in the housing 2, when sufficient dynamic force is applied to the housing 2 to cause the member 10 to shear off the shear pins 12, thus causes the contact 18 to engage the contact 20 and close the electric circuit 26, 28 through the solenoid coil 30 to effect the closing of a second switch 32 in a motor operating circuit 34 by which a motor 36 is actuated to operate any suitable valve-closing mechanism.

As hereinabove suggested, the apparatus of the present invention is particularly useful in closing shut-off valves to steam lines of naval vessels which may have been injured by the shock of an explosion, such as that of a torpedo or a mine. The action of dynamic forces such as these is so nearly instantaneous that it is important that provision be made for insuring the maintenance of a circuit, which has been closed as a result of such action, for a sufficient length of time to insure the actuation of the main valve closing mechanism. This may be effected in various ways as, for example, by the employment of an ordinary tiltable mercury tube switch which would remain in its switch-closing position when tipped thereinto oil, as in the case of the illustrated circuit-closing means, locking means may be provided for locking the inertia member 10 in its switch-closing position. In the illustrative embodiment of the invention, simple spring catches 38 are provided, there being four of these shown as spaced 90° apart about the inside of

the guide housing 2. These catches 38 are pressed into recesses 40 in the housing when the inertia member 10 is in the position shown in Figure 1, but spring out over the top of the member when it moves downward in the guide housing 2, thus locking it against movement upward.

From the foregoing description, the operation of the device will readily be understood. Assume that the guide housing 2 is connected to a steam main or other steam line of a naval vessel and that the dimensions and resistance to shearing of the pins 12 have been so determined with respect to the weight of the inertia member 10 that said inertia member will follow the movements of the guide housing 2 as said housing in turn follows the movements of the steam main, or other steam line, to which it is attached, in the ordinary operation of the naval vessel, including such movements as are brought about by the dynamic forces produced by the firing of the guns of the vessel, by the impacts of heavy seas against the sides of the vessel, etc. If, now, the vessel should strike a mine or should be hit by a torpedo, so that the steam main or other steam line would be subjected to the action of a dynamic force of greater intensity than that for which the shear pins 12 have been calibrated, the resistance of the inertia member 10 to movement with the guide housing 2 would cause the shear pins 12 to shear off, thus bringing the contact member 16 into engagement with the contact member 20 by the relative movement of the inertia member 10 and the guide housing 2, thereby closing the circuit 24, 28 through the solenoid 30 and in turn closing the switch 32 in the circuit 34 that operates the motor 36. The springing of the spring catches 38 into position above the inertia member 10 would then prevent the re-opening of the switch 18, 20 and thus insure maintenance of the circuit 24, 28 for a sufficient time to operate the switch 32.

What I claim as new is:

An automatically protected distributing system for dangerous fluids which comprises, in combination with a reservoir of dangerous fluid and a distribution pipe line extended so as to be subject to shock of such force as may cause breakage of the line, an inertia member, a guide for said member so mounted upon the pipe line for protection of which said device is intended as to partake of the same movements as the part of said pipe-line which is subject to destructive shock, an electrically operated shut-off adapted to control the admission of the dangerous fluid to said pipe line and positioned at a point remote from the inertia member, an actuating circuit for said shut-off including a switch arranged to be operated by movement of said inertia member in its guide, and means for securing said inertia member to said guide so that said member also partakes of the same movements as said pipe line up to a predetermined dynamic limit, but said securing means being yieldable to a force encountered when said dynamic limit is passed, whereby said inertia member is moved by such force to operate said switch and thereby to actuate said shut-off.

JOSEPH KAYE WOOD.
